UNITED STATES PATENT OFFICE

WILLIAM H. GIBSON, OF CINCINNATI, OHIO, ASSIGNOR TO GIBSON ART COMPANY, OF CINCINNATI, OHIO, A CORPORATION OF OHIO

CARD-DECKLING MACHINE

Application filed November 19, 1928. Serial No. 320,361.

The essential object of this invention is to provide a simplified method of producing a rough or "deckle" edge effect on paper sheets or cards.

5 A further object is to provide a simple and effective mechanism by which the above outlined method may be carried out.

Further objects and features of the invention will become apparent from the following description relating to the accompanying drawings, wherein I show the preferred form 10 of machine. The essential novel characteristics are summarized in the claims.

Greeting cards and the like are treated to 15 obtain the effect known as deckle edge by various processes, usually including the step of tearing a large sheet into two or more smaller sheets. This, even though several sheets may be treated at once, is very expensive. The 20 present invention is essentially concerned with a novel method of deckle edging wherein the blanks are originally cut to proper size, are held in stacked relation, and the whole stack then operated upon by a tool having an 25 irregular edge, that is to say, an edge, the contour of which is the converse of that desired for the sheets or cards.

In brief, the process, as preferably practiced, comprises assembling a convenient 30 number of blanks in stacked relation with the edges lying substantially in a common plane, clamping the stack in a portable frame, then moving the frame while supported by the stack of blanks across a smooth surface adjacent one edge of which surface the tool 35 operates with a chopping motion to progressively produce the deckle edge effect on all the blanks in the stack.

The mechanism shown comprises, in brief, 40 a base, the top side of which forms two separated smooth surfaces. Operating between these surfaces is a rotary tool which has its cutting edge suitably indented to obtain the desired sheet or card contour. The blanks 45 are mounted in an open clamping frame adapted to be shifted manually to carry the blanks over the top surfaces of the base and into operating contact with the tool.

A further refinement consists in mounting 50 the stack in such manner that irrespective of

clamping pressure on the stack, the latter may be easily turned with reference to the clamping frame to present all four edges, one after the other, to the tool.

Still further refinements of the mechanism 55 include adjustable guiding and supporting means for the stacked blanks by which cards or sheets of widely varying dimensions may be effectively operated upon in the same machine.

A further feature is the provision of mechanism 60 for sharpening the deckle edging tool, by which the tool may be ground without removing the same from the machine.

In the drawings, Fig. 1 is a side elevation 65 of the machine set up for operation; Fig. 2 is a similar side elevation of the machine adjusted for sharpening the tool; Fig. 3 is a substantially central longitudinal cross sectional view of the machine with the tool grinding mechanism in operative position; Fig. 3^a is a fragmentary sectional view of a suitable deckle edging tool; Fig. 4 is a cross sectional view of the machine taken along the line 4-4 of Fig. 3; Fig. 5 is a cross sectional view of the machine taken along the line 5-5 on Fig. 3; Fig. 6 is a substantially 70 central longitudinal cross sectional view of the blank clamping frame; Fig. 7 is an end elevation of the mechanism shown in Fig. 6, and Fig. 8 is a detail view of part of the 75 blank clamping frame.

Referring again to the drawings, 1 indicates a suitable base upon which rests a plate 2. The plate 2 is extended at one side of the 80 machine as at 2^a in Fig. 4 for supporting a suitable driving mechanism for the deckle edging tool as well as for supporting the tool grinding mechanism. Resting on the plate 2 and secured thereto is a hollow sub-base 3, 85 the top portions of which incline toward each other, as suggested in Fig. 3, the edges of the inclined top being suitably formed as at 6 to provide trackways for individually adjustable tables 7 and 8. The tables have 90 bridging top members 9 and 10 respectively carrying smooth surfaces over which the stacked cards are slid toward and away from the deckle edging tool. Suitable means, such as screws 12, provided with hand wheels 13 95 100

and engaging ears 5^a on the sub-base 3, serve to adjust the top surfaces of the tables relative to each other, if desired, and to the tool.

The tool, as shown particularly in Fig. 3^a, 5 preferably comprises a plate 20 bevelled at its top edge, as at 20^a, and provided with depressions 20^b preferably of irregular contour and spacing. One or more of these tools may be supported on a suitable shaft 21 positioned transversely of the machine in suitable bearings (not shown) and arranged to be driven by an electric motor 23 (Fig. 5), resting on the extension 2^a of the plate 2. The shaft 21 may be recessed as at 24 to receive the tool and the tool may be adjustably positioned in the recess by a series of cap screws 25, one being shown in Fig. 3. Adjacent the recess 24 is a second recess 26 arranged to afford clearance for a grinding 10 tool, to be hereinafter described, shown in Fig. 3.

The card or sheet holding and clamping device, as shown particularly in Figs. 1, 6 and 7, comprises two end frame members 25 and 26, each having a pair of horizontally extending arms 27, one pair being shown in Fig. 7, and a single upright arm 28. The arms 28 serve as handles for shifting the frame over the table surfaces. The members 25 and 26 are joined together by horizontal rods 30, 31 and 32 provided with suitable nuts 33 for spacing the members 25 and 26 in parallel relation, and suitable nuts 34 for holding the members 25 and 26 together.

35 Journalled in the member 25 is a short axially fixed shaft 35 having an enlarged head at its inner end, designated 36, and a projection 37 on which is mounted a clamping plate 38, preferably wood. The shaft 35 is held in place by a disc 40 suitably keyed to the shaft and overlapping the end surface of the member 25. The inner surface of the disc has circumferentially spaced recesses 41, the recesses being spaced substantially 90° from each other. A suitable plunger 43 seated in the member 25 and acted on by a spring 44 coacts with the recesses 41 to thereby hold the shaft 35 in various 90° turned positions relative to the frame.

50 The block of blanks is shown diagrammatically at S in Figs. 1, 6 and 7. The blanks are clamped against the plate 38 and a movable plate 45 similar in construction to the plate 38 and supported on an extension 46 55 of a short shaft 47 which is in turn supported in the enlarged end 48 of a clamping screw 49. The screw 49 engages internal threads in a bushing 50 rigidly carried by the member 26, and the outer end of the screw may be suitably 60 formed as at 51 for engagement with a wrench.

In order that the block S may be easily turned with reference to the frame, the shafts 35 and 47 are each provided with antifriction 65 thrust bearings 36^a and 47^a, shown as ball

bearings of a common type. The races of the bearing 36^a are respectively positioned adjacent the head 36, and the member 25 and the races for the bearing 47^a are respectively positioned between a head 53 on the shaft 47 70 and the enlargement 48 of the screw 49. Suitable means, such as a threaded pin 54, the end of which bears in a peripheral groove 55 on the shaft 47 may be employed to prevent endwise removal of the shaft 47 from the screw while permitting the shaft 47 to turn freely. It will be seen that by the arrangement of bearings and associated parts, the block of sheets or cards may be turned as a unit by hand with reference to the frame 80 without releasing the clamping force of the screw, and held in the turned position, so that any or all sides of the block may be positioned face down for operation thereon by the deckle edging tool.

85 Suitable means for preventing the blanks from becoming freed as by reason of the screw 49 creeping within the bushing 50, in a direction to cause the clamping plate 45 to withdrawn from the blanks, may comprise a ratchet wheel 57 preferably keyed to the screw by means of lug portions 57^a of the wheel entering longitudinal slots 58 on the screw, and a cooperating pawl 59 mounted on the frame member 26. The pawl may be 90 suitably supported as by a stud 60 and urged toward the ratchet teeth by the usual torsion spring indicated at 61. The ratchet wheel 57 may be prevented from axial movement by means of a plate 63 secured to the member 26 95 and having a bent portion 64 embracing the screw shank and lying outwardly from the wheel, the bent portion bearing directly against a washer 66 which in turn directly 100 engages the wheel.

105 Suitable means for guiding the block of blanks as the same travels across the top of the machine from one table to another may comprise guide rails mounted on the table members 7 and 8. Preferably the guiding means comprises a T-rail 70 (see particularly Fig. 5) having one surface resting on the tables as at 71. The rail extends across from one table to another and may be supported by brackets 72 (see Figs. 2, 3 and 5) recessed as 110 at 73 to contain the armed portion of the rail and having an overhanging plate 74 completing a slidway for the rail. The T-rail, as shown in Fig. 2, is withdrawn from contact with the table 7 to clear the tool 20 for 115 grinding the same as will be presently shown, and the left hand end of the rail is shown as bevelled as at 75. When the rail is in its normal position (Fig. 1) the bevelled end abuts a fixed guide rail section 77 secured to 120 the table 7 in registration with the T-rail.

125 In addition to the guide 70 it is desirable to provide an auxiliary guide on the side of the block of blanks opposite the rail 70 partly to prevent the frame with the block from 120

being accidentally slid off the table onto the floor. Such supplemental guide is shown as comprising a bar 80 removably secured to a horizontal strip 81 supported by brackets 82 fixed thereto, the brackets in turn being supported by transverse rods 83 and 84 in respective tables 7 and 8. The brackets may be secured tightly to the rods and the rods may be longitudinally adjustable in bushing members 85 secured in transverse bores in the members 7 and 8.

The primary purpose of the plate 81 is to support blanks of greater width than are ordinarily operated on by the machine, that is to say, should the blanks be of greater length than the tool, there should be means to support the overhanging ends of the blanks during their entire travel along the table. The strip 81 and guiding bar 80 may be positioned away from the table a distance determined by the length of the rod 83. Suppose, for example, that the main surfaces of the table measures 8 inches transversely of the machine, then by withdrawing the rods the table width may be effectively increased to support say a 16 inch blank.

When operating on blanks requiring adjustment of the table, as above outlined, part of the block of blanks is deckle edged on one sweep of the blank holding frame across the table, whereupon the frame is turned end for end and the deckle edging completed, as to the remainder of the block. In this connection, it is to be noted that it is within the spirit of my invention to provide for reversing the shaft 21, as well as the direction of rotation of the shaft driving means, whereby when the frame is turned as aforesaid and the deckle edging operation completed, the burr formed by the deckle edging process on the individual cards or sheets will be uniform. It may be mentioned that with the majority of cards, particularly hard surfaced cards, there is no perceptible burr, hence unusually large cards of this nature may be deckle edged without having to reverse the direction of operation of the tool.

In order that the tool 20 does not have to be removed from the machine each time it becomes dull, I preferably provide mechanism for sharpening the tool as part of the machine, but which may be normally swung to a position on the machine in which it will not interfere with the deckle edging operation. Such arrangement, as shown, comprises a slideway affording member 90 (see Figs. 1, 2, 3 and 4) having a depending arm 91 pivotally secured as by a pin 92 to a bracket 93 on the extension 2^a of the plate 2. The slideway member 90 supports a base member 95, the latter having side extensions 96 engaging beneath overhanging plates 97 on the member 90 which form part of the slideway. The base 95 supports a motor grinder 100. The grinder has a frame 101 provided on its lower

side with bevel-sided extensions 102 guided by overhanging parts 103 and 104 on the base 95. The part 104 is shown as removably attached to the base as by a stud 106. The motor frame 101 may be shifted bodily transversely of the slideway 90, to adjust the grinder with reference to the tool 20, by means of a screw 107 rigid with the member 102 of the motor frame and extending through an ear 108 on the base 95, there being a hand nut 109 on the screw engaging the ear 108.

The motor casing has an extension 111 supporting the motor shaft 112, and a suitable grinding tool is mounted on the end of the shaft as at 113. The grinding tool, it will be seen, may be adjusted toward and away from the deckle edging tool 20 by means of the nut 109 and the whole grinding mechanism, including base 95, may be shifted manually across the machine on the slideway 90 to grind the whole cutting edge of the deckle edging tool.

During operation of the grinder, the slideway and associated parts may be held in fixed position above the machine by reason of a member 115 depending from the free end of the slideway member 90 and carrying a pin 116 arranged to be engaged by a hook 117 pivoted as at 118 on a bracket 119 secured to the sub-base 3. The lower end of the member 115 engages the bracket 119 as an abutment. A suitable handle 120 on the endwise extension 95^a of the block 95 serves to raise the slideway and associated parts to the position shown in Fig. 1, after the grinding operation is completed.

Suitable means for preventing movement of the grinding motor and supporting base 95 along the slideway when the slideway member 90 is raised may comprise a spring pressed button 122 carried by the extension 95^a and arranged to engage the end of the slideway as in Fig. 1 or, if desired, suitable apertures in the bottom of the slideway.

I claim:

1. The method of treating sheet material to obtain a deckle edge effect, comprising stacking the sheets, compressing the stack, and moving the stack, in a direction normal to the plane of a sheet in the stack, relative to and in intermittent contact with a rapidly revolving undulating cutting edge.

2. The method of treating paper sheets and cards to obtain a deckle edge effect, comprising stacking the sheets or cards, compressing the stack, and moving the stack past and in intermittent contact with a rapidly revolving knife having an undulating cutting edge.

3. The method of producing a deckle edge effect on sheet material, comprising assembling a stack of sheets with corresponding edges thereof substantially in a common plane, clamping the stack in a frame, moving the frame across a substantially smooth

surface while supporting the frame by the stack of sheets, and progressively chopping the edges of the sheets as the same ride off such surface.

5. In mechanism of the class described, a table, a rotary tool adjacent said table, a frame movable over the table and tool, and blank holding means associated with the frame arranged to hold a stack of cards or 10 the like in the frame in edgewise contact with the table for movement thereover to the tool.

5. In mechanism of the class described, a table formed to present separated top surfaces, a revolving member positioned between such surfaces, a tool carried by said member extending lengthwise thereof and having an undulating edge, and means movable over said table and arranged to hold a stack of sheets in compressed condition and 20 edgewise contact with the table.

6. Mechanism for deckle edging cards and the like, comprising a table presenting separated top surfaces, a rotary tool positioned between such surfaces, means for driving the 25 tool, means for raising and lowering the table with reference to the tool, and means for clamping a stack of such cards into a unit for movement over the table, the table engaging the edges of the sheets or cards and 30 guiding the same to and past the tool.

7. In mechanism of the class described, in combination, a base, table means on the base providing table surfaces in separated relation to each other, a rotary tool positioned 35 between said separated surfaces and mounted on the base, said tool presenting an undulating cutting edge, a mounting for a stack of blanks arranged to be shifted across the table means from one said surface to the other to carry the blanks into engagement 40 with the tool, said blanks having their edges in direct engagement with the table surfaces and supporting the mounting.

8. In mechanism of the class described, a 45 table providing separated top surfaces substantially in a common plane, a rotatable tool positioned between said surfaces and having an undulating cutting edge, a portable frame adapted to support a block of 50 paper sheets or cards engaging the table edgewise and arranged to be shifted across the table from one surface to another for operation thereon by the tool, there being a block guiding rail supported by said table 55 at one side thereof and extending in bridging relation to said table surfaces.

9. In mechanism of the class described, a frame adapted to embrace a block of sheet material, means carried by the frame arranged 60 to exert clamping pressure on the opposite ends of the block and including a pair of block engaging members, there being 65 antifriction means associated with the said members to permit the block to be manually turned with reference to the frame without

releasing the clamping force on the block.

10. In mechanism of the class described, a portable work frame comprising end members, each having lateral and upstanding arms, the latter serving as handles, means 70 joining the arms to hold the end members mutually rigid, clamping devices turnably mounted on the end members, one clamping device including a screw supported in a respective end member, and means on such latter member for locking the screw in adjusted position.

11. In mechanism of the class described, a deckle edging tool, and means for driving the same, a guide for presenting work to the tool, and means for holding the work comprising a frame, relatively movable clamping members on the frame adapted to hold work in compressed condition, and antifriction means associated with the clamping members whereby the work may be manually turned at right angles with reference to the frame without releasing the clamping pressure.

12. In mechanism of the class described, portable work holding means comprising a frame adapted to embrace and hold a block of blanks, two turnable members supported by the frame for abutting opposite ends of such block, clamping means carried on the frame and operatively engaging one of said turnable members to clamp the block, and means acting on one of said turnable members for holding the block in a plurality of 95 predetermined angular positions relative to the frame.

13. In mechanism of the class described, portable work holding means comprising a frame adapted to embrace and hold a block of blanks, a turnable member arranged to abut one end of such block, a turnable member for abutting the other end of the block, a clamping screw operatively engaging one of said members, means connected with the 110 screw and arranged to hold the screw in clamping position with relation to the blanks, and means acting on one of said turnable members for holding the stack in various turned positions relative to the frame.

14. In mechanism of the class described, a portable work holding frame comprising end members, and means connecting the same, clamping devices carried on said end members and arranged to engage the work from opposite directions, a screw carried by one of the end members operatively engaging one of said clamping devices, there being ratchet means on the end member supporting the screw for locking the screw in blank clamping position.

15. In combination, a work supporting frame, a tool carried by the frame, and tool grinding means movably supported by the frame and arranged to traverse the work 130

supporting portion thereof in contact with the tool.

16. In mechanism of the class described, means providing separated table surfaces, means to move work along the table from one surface to the other, a power driven tool positioned between said surfaces and arranged to engage the work, and power driven tool grinding means attached to and movable into and out of position across said table for 10 sharpening the tool.

17. In mechanism of the kind described, a table, a tool supported by said table adjacent the top surface thereof, means for guiding work along said table into contact with the tool, a guide mounted for movement into and out of position across the table and arranged to extend transversely of the direction of movement of work on the table, and tool grinding means arranged to traverse the 20 guide while in contact with the tool to sharpen the edge thereof.

18. In mechanism of the kind described, a table providing separated top surfaces, a rotary tool positioned between such surfaces 25 and adapted to operate on work supported thereby, a guide rail for work extending from one surface to the other, means for sharpening said tool movably mounted on said table and arranged to traverse the entire length 30 of the tool, and means slidingly supporting the guide rail whereby the same may be moved entirely clear of one of the table surfaces to thereby clear the tool for the sharpening 35 operation.

35 In testimony whereof, I hereunto affix my signature.

WILLIAM H. GIBSON.
